UNITED STATES PATENT OFFICE.

JOHN E. ENNIS, OF DULUTH, MINNESOTA.

BRICK-MARKING MACHINE.

SPECIFICATION forming part of Letters Patent No. 483,910, dated October 4, 1892.

Application filed October 29, 1891. Serial No. 410,296. (No model.)

To all whom it may concern:

Be it known that I, JOHN E. ENNIS, residing at Duluth, in the county of St. Louis and State of Minnesota, have invented a new and 5 useful Brick-Marking Machine, of which the following is a specification.

My invention has for its object to provide a brick-marking device especially adapted for use by brick-masons, by means of which bricks 10 can be quickly marked and gaged to facilitate the laying thereof; and it consists in the peculiar combination and novel arrangement of parts, all of which will hereinafter be fully described in the specification and particularly pointed out in the claims, reference being had to the accompanying drawings, in which—

Figure 1 is a top plan view, partly in section, of my improvement. Fig. 2 is a front 20 sectional elevation taken on the line 2 2, Fig. 1. Fig. 3 is a cross-section of the same on the line 3 3, Fig. 1. Fig. 4 is a vertical section of one of the inking devices. Fig. 5 is a detail section taken on the line 5 5, Fig. 1.

In the practical method of laying bricks it is 25 very essential, especially in fine press-brick work, that the bricks are properly gaged, so that the mason can produce a finished job in which the struck joints are all uniform and even. To this end it is usual for the helper 30 to measure the bricks and then mark them to indicate their thickness. This method of sorting the bricks is both slow and unreliable, as the measuring is usually done by unintelli- 35 gent persons, to whom the necessity of exactness of measurement is not always apparent. Furthermore, it is not usual to mark the bricks to indicate their length, which causes the mason in laying them a great deal of trouble 40 in fitting or matching them so as to make a straight joint.

My improved device is intended to provide means whereby the operation of marking can be rendered speedy and regular and whereby 45 the thickness, as well as the length, will be indicated thereon, and, furthermore, it also provides for making a special mark at any point on one of its faces, which indicates the point at which they need be cut when it is desired 50 to provide for a number of short bricks to fill in any given points in the wall or pier.

Referring to the accompanying drawings,

A indicates a suitable base-frame, on which are pivotally mounted the end standards B B, in which is journaled a rock-shaft C, upon 55 which near the standards B B are loosely mounted the rocking frames D, the outer faces d of which are segmental, but arranged eccentric to the shaft C, for a purpose presently explained. The lower ends of the 60 frames D are projected horizontally inward, as at d', and form bearings for rollers d''. Such frames have also inwardly-projecting diagonally-disposed flanges or cam-faces D', as most clearly shown in Figs. 1 and 3 of the 65 drawings, such frames being held to their upper or normal positions by the springs D'' D'', as shown. Adjacent the frames D segmental frames E are fixedly secured to the shaft, which are adapted to be swung inward and 70 to rock on the shaft C for a purpose hereinafter stated, such shaft being held to its normal position by means of spring C''. (See Fig. 1.) These plates E are formed with open portions E' and with lock-notches e, into 75 which lock-bolts F are normally projected and which serve to hold such plates E and the shaft from rocking while they engage the said notches. The lock-bolts F consist of lateral projections on the upper end of angular arms F', journaled at f between lugs f' f' on the base A, the rearwardly-extending members f'' bearing on springs f'', which serve to normally throw the pivoted angular arms to their locked position. 85

G G' G'' indicate a series of marking-rollers located between frames E, as most clearly shown in Fig. 1, and such rollers are journaled each in a frame g, journaled at its lower forward end in the brackets a'' a'', and each of 90 such frames g is formed with an ink cup or pocket g', with which connects a feed-channel g'', which extends up under the inking-rollers in a manner clearly shown in Fig. 4 of the drawings, and to provide for feeding the 95 ink to such rollers each of the ink-pockets is internally threaded at its upper end, into which fit threaded plugs g'', which as the ink is used up are screwed down into the pockets and serve to force the ink therein up to the 100 rollers. Extended rearward from the pockets g'' are horizontal arms g'', the outer apertured ends of which fit over vertical extensions a'' on the base, the upper ends of which

are threaded to receive adjusting-nuts a^5 , springs a^6 being interposed between the said arms g^4 and the base A, which serve to hold the inking-roller frames to their operative or normal positions. By arranging the inking-roller frames in the manner shown they are capable of independent adjustment for a purpose hereinafter explained. At one end of the base is pivoted a base-plate H, as shown at h , which carries inking-rollers and frames $H' H^2 H^3$, which are constructed and arranged in a manner similar to the rollers G G' G². Such end plate H and its inking-roller I term the "end-marking devices," as they are employed to mark the ends of the bricks. The base of such plate has an elongated slot h' , through which the pivot-bolt h passes, as shown. By this construction, when desired, the plate H can be swung around to the position shown in dotted lines in Fig. 1, in which position it will serve to mark the end of the outer side or face of the brick.

J indicates a plate secured to the base-frame A at a point opposite and in front of the roller-frames g, which is formed with the vertical end frames J', the inner faces of which are recessed longitudinally at j , in which is journaled a series of guide-rollers J'.

J² J³ indicate a pair of parallel-arranged shafts, one of which J² is held between the frames J', while the shaft J³ is held between the short bearing j , as shown. Upon these shafts J² J³, held to be moved longitudinally, is an inking-roller and frame K, which roller is arranged to be set at any point desired on the shafts J² J³, so as to mark all the bricks at any given point.

At the end of the base A, at a point opposite the end-marking rollers H' H² H³, is secured a frame L, formed with a vertical member having its inner face recessed, in which is journaled a number of guide-rollers l l. When the rollers G G' G² are adjusted to the position shown in Fig. 1—i. e., the roller G² projecting beyond the roller G' and the roller G' beyond the roller G—and the end rollers H' H² H³ adjusted in a similar manner, the device will then be ready for marking. It should be stated, however, that the relative arrangement of the end guide-rollers l, the side guide-rollers J, the central inking-roller G, and the first end roller H' is such that a brick of the average length and thickness will just fit between them. The frames D, which are loosely journaled on the shaft C, and the rock-frames E, which are fixedly secured thereto, are constructed in the manner before described to operate to insure the brick entering between the inking-rollers in a horizontal position, whereby its true measurement will at all times be assured.

To use the device, the operator grasps the brick lengthwise and uses the end and side rollers l and J as his guide forces the brick downward, and in doing so should the brick be entered in a diagonally-inclined position its lowest end would engage one of the roll-

ers d on the frame, which would rock such frame on the shaft until it assumes the position shown in Fig. 5, and as such frame is brought to the said position in the manner stated its flange member will engage the lock-bolt F and force it and its supporting-frame F² back to the position shown in said Fig. 5, and thereby unlock the rock-frame E from the frame D. At this time the lower edge of the brick will come in engagement with the frame E, (see dotted lines in Fig. 5,) and as such frame is rigidly connected with the shaft C and as the opposite frame D has not been operated or engaged by the brick to unlock the opposite frame E it (the brick) is held from further downward movement at such end, and as the opposite end is brought down it will engage the opposite frame D in a similar manner until its lower end depresses it to the same horizontal plane as the opposite frame D. At this time both of the frames D and E will be disengaged, and the brick, now engaging the frames E, will, as it is further depressed, rock such frames and the shaft C downward to permit the brick engaging the inking-rollers, which as it pushes down turns such rollers to cause them to become inked up, and after the brick has been depressed to its lowermost limit it is quickly withdrawn, and as it rises up it turns the freshly-inked rollers in a reverse direction, which then mark the brick according to its shape. It will be noticed that by adjusting the inking-rollers in the manner stated should a brick of less than the average thickness be inserted the roller G² will engage its side and make a single mark, should its thickness be the average both the rollers G² and G' will engage it and make two marks, or should the brick be more than the average thickness all three of the rollers G' G² G³ will engage it and leave three marks. It will be also noticed that should a brick be of less than the average length the roller H' will engage and mark the end of the brick, if of average length both rollers H' and H² will mark it, and if greater than the average the three rollers H' H² H³ will engage it.

It is sometimes very necessary in building that a number of bricks be short—say six inches in length—to fill in at given points in the wall. To this end the roller K can be adjusted on the shafts J² J³ to make a single mark at the point desired on the face of the brick. Thus it will be seen that each brick will be marked to indicate its thickness, its length, and to indicate where to cut for the standard short brick required in the work.

In some instances, especially so in pier-work, where it is frequently necessary to run courses of short or long bricks and where it is also frequently required to cut off the end of a brick one-half to one and a half inches, I adjust the end-marking devices to mark the sides of the brick at the outer ends. In this case the rollers H' H² H³ can have their marking-faces in the same plane, as the first roller

will serve to mark the short, the second the average, and the third the longer brick, such marks being arranged to indicate half-inches.

The advantages of my improved marking devices will be readily understood from the foregoing, taken in connection with the drawings. Its uses will be readily appreciated by those skilled in the art of building.

Having thus described my invention, what I claim, and desire to secure by Letters Patent, is—

1. A brick-marking machine comprising side and end guides for guiding one end of the brick and movable guides for the opposite end of the brick, said guides carrying marking devices adapted to simultaneously mark the end and side of the brick, substantially as and for the purpose described.

2. A brick-marking machine having fixed end guides and marking devices arranged to engage the face of the brick and adapted to be set relatively to the fixed end guides, whereby to mark the face of the brick at a given point on its face, substantially as and for the purpose described.

3. A brick-marking machine comprising end and side guides and marking-rollers having their marking-faces arranged in different planes, whereby to be set in marking position to engage bricks of different thicknesses, as and for the purpose described.

4. In a brick-marking machine, the combination, with the side and end guides and the base, of a marking device adjustably held on the base and adapted to be set to mark the face or end of the brick, as and for the purpose described.

5. In a brick-marking machine, the combi-

nation, with the guideways and the marking devices arranged as shown, whereby to form a pocket-like portion, of restraining devices adapted to hold the brick from engaging the marking devices when inserted in the pocket diagonally and arranged to be released and depressed by the brick when it is entered horizontally in such pocket portion, substantially as and for the purpose described.

6. In a brick-marking machine, the combination, with the guide-rollers and the inking devices arranged as shown, of the rock-shaft C, the frames D, loosely mounted thereon, the frames E, fixedly connected to the shaft C, and the locking-frames F' F, said frames D arranged, when moved, to unlock the frames E and F, substantially as and for the purpose described.

7. In a brick-marking device, substantially as described, the combination, with the side guides, of an inking-roller spring-actuated and normally held out to its operative position and means for adjusting its marking-face relatively to the said guides, substantially as and for the purpose described.

8. In a brick-marking machine, the combination, with the fixed end and side guides, of a marking device consisting of a plurality of marking-rollers having each a yielding bearing, whereby two or more of such rollers can be brought in the same plane by the insertion of a brick between the fixed guides and said rollers, substantially as and for the purpose described.
